UNITED STATES PATENT OFFICE

RENÉ CLAVEL, OF BASEL, SWITZERLAND

LOADING OF SILK, OR SILK-CONTAINING TEXTILE MATERIAL

Application filed July 9, 1928, Serial No. 291,292, and in Switzerland August 23, 1927.

The present invention relates to an apparatus for loading natural or artificial silk textile material, or textile material containing natural or artificial silk of suitable type, for example in the form of yarn, hanks or skeins or runs, or in the form of fabrics, in which the textile material can be sufficiently loaded without trouble in the shortest period in a continuous process without interruption by washing, acidification, or neutralization between the separate working stages.

The loading of natural silk, or natural silk-containing material, without washing, acidification, or neutralization of the textile material coming from one loading bath before transference into the succeeding loading bath, which is disadvantageous from both the manufacturing and economical points of view, has first been rendered possible by the knowledge that this troublesome intermediate treatment of the textile material can be dispensed with, if the treatment of the textile material with the solution of metallic salt required for the loading, for example stannic chloride, is carried out in the presence of acids or acid salts which either act on the textile material before treatment with the metallic salt, or are added to the solution of the metallic salt.

It has only been possible to load artificial silk or products containing artificial silk more particularly, without any troublesome technical objections, after the above knowledge had been acquired.

The present invention consists of a chamber provided with closure means and containing one or more supports or carriers for the textile material, the lower portion of this chamber being constructed as a receptacle for the loading liquid and being connected up with a pipe system having a feed mechanism which allows of circulation of the loading liquid, charging of the receptacle with the loading liquid, and discharge, the loading liquid being returned if necessary to the supply vessel.

It is advisable to use horizontal stationary or rotating hollow supports for the textile material to be loaded, which supports are provided with fine apertures on their periph-

ery and are connected to the circulation system for the loading liquid. Simple cylindrical pipes with peripheral apertures are particularly suitable for use as hollow members of this type. The chamber itself in which the loading of the material is carried out is provided with a mechanism for removing excess loading liquid from the textile material and vapours in the chamber. This extractor preferably operates through the apertures in the peripheral wall of the hollow supporting member.

In order to clean the loading apparatus it is preferable to attach a water pipe to the pipe system for circulating the loading liquid, whereby all the pipes, and the chamber can easily be washed out.

The invention is more particularly described by way of example with reference to the accompanying drawings in which:

Figure 1 is a side elevation and

Figure 2 is a partial plan view of the improved apparatus.

A suitable number of hollow supporting members having apertures in the walls, for example cylindrical pipes 3 with a plurality of apertures in the top portion, are arranged horizontally in a tank or vessel 1 which is adapted to be closed by means of a door and the lower portion of which is constructed as a reservoir 2. A pipe 4 leads from a number of vessels A, B, C, and D, containing the separate loading liquids, into the reservoir 2.

Valves 5 are adapted to supply loading liquids from the vessels A, B, C and D separately or together to the reservoir 2 in suitable sequence. The reservoir is provided with two outlet pipes 6 and 7 with valves 8 and 9. The outlet pipe 6 with the valve 8 allows of running the liquid out of the apparatus, whilst the outlet pipe 7 and valve 9 is connected with a centrifugal pump 10.

This pump 10 feeds the liquid coming from the reservoir 2 through a pipe 11, and thence either through a valve 13 according to the position through a pipe 15 and into the supporting members 3, which can if necessary be rotated by means of a mechanism 14, and are provided with outlet apertures for the liquid, or through a valve 12, pipe 16 and

one of a number of valves 17a, 17b, 17c, 17d, into the corresponding vessels A, B, C and D.

A water pipe 18 and valve 19 are adapted both to wash the supporting members 3 with water through the pipes 11 and 15, and also 5 to clean out the reservoir 2. The water is then led away through the outlet pipe 6.

A vacuum pump (not shown) is connected by means of a pipe 20 and valve 21 with the 10 supporting members 3, and is adapted to remove the excess liquid from the textile material located on the supporting members 3.

The operation of this apparatus is for example as follows.

The textile material to be loaded is suspended on the supporting members 3; the chamber 1 is closed and the valve 5 of the vessel A, which contains the pre-treatment liquid, for example formic acid, and also the flow valve 22 are opened until sufficient liquid has flowed into the reservoir 2. On opening the valve 9 the acid flows to the centrifugal pump, which is in operation and on closing 20 the valve 12 and opening the valve 13 is pumped by it through the pipes 11 and 15 into the supporting members 3, which are also rotating if necessary, flows through the apertures therein, saturates the textile material and flows down the latter to collect in the 25 reservoir 2 again. After treatment lasting several minutes—the acid under certain circumstances makes one circuit through the reservoir 2, pump 10 and supporting member 3—the liquid is returned to the vessel A through pipes 11 and 16 by closing the valve 35 13 and opening the valves 12 and 17a.

The contents of the vessel B are then brought into circulation in similar manner, 40 in order to treat the material with the loading agent, for example a solution of stannic chloride contained in the vessel B, for about five minutes. The extractor can now be brought into operation on closing the valve 45 13 and opening the valves 21 and 24 whereby on intermittent operation of the vacuum pump and simultaneous rotation of the supporting members by means of the rotational mechanism 14 the excess liquid is gradually 50 removed from the textile material which at the same time comes in contact with the air, before the further treatment.

An extractor adjustable according to the amount of the material, arranged at points 55 other than the point of suspension of the goods, may also be provided instead of the extractor operating through the supporting tubes.

The material is then saturated in the 60 same manner with the fixing solution, for example a phosphate solution contained in the vessel C and after circulation for about six minutes, this liquid is returned to the vessel C. The valves 12 and 17c are then 65 closed and the apparatus is thoroughly

washed out with water from the pipe 18 by opening the valves 19 and 8.

After closing the valves 19 and 8 and opening the valve 22 the material is further treated in the manner described with an additional loading liquid, for example sodium silicate solution present in the vessel D, and after pumping the excess liquid back into the vessel D, is washed out with water by opening the valves 19 and 8 after closing the valves 12 70 and 17, whereon the material fully loaded is dried.

Instead of the liquid being supplied through the supporting members provided with outlet apertures, it can also be supplied 80 for example by being sprayed externally through special devices on to the material laid or suspended on supporting members.

Considerable advantages both as regards the quality of loaded material and also the 85 duration and saving in material are obtained by treatment of the silk-containing textile material in a single apparatus, without removing the material and without any washing, acidification and neutralization between 90 the separate treatments.

Having now particularly described and ascertained the nature of my said invention and in what manner the same is to be performed, I declare that what I claim is:

1. An apparatus for loading silk or silk-containing textile materials comprising a tank forming a reservoir in the lower portion thereof; a plurality of liquid supply vessels; means for connecting said vessels with the tank to supply liquids thereto; means in the tank for supporting the textile materials to be loaded; means for circulating fluids through the materials; and means for extracting the fluid from the textile materials through the supporting means for the materials. 100

2. An apparatus for loading silk or silk-containing textile materials comprising a tank forming a reservoir in the lower portion thereof; a plurality of liquid supply vessels; a plurality of hollow supporting members in the tank having fine outlet apertures therein, said members acting as supports for the materials to be loaded; means for connecting said members with said vessels to supply liquids to the materials through the apertures; and means for extracting the liquids from the textile materials through the outlet apertures in supporting members. 110

3. An apparatus for loading silk or silk-containing textile materials comprising a tank forming a reservoir in the lower portion thereof; a plurality of liquid supply vessels; a plurality of hollow supporting members in the tank having fine outlet apertures therein, said members acting as supports for the materials to be loaded; means for connecting said members with said vessels to supply liquids to the materials through the apertures. 115

tures; means for forcing the liquids from the vessels through supporting members and tank back to the vessels; and means for extracting the liquids from the textile materials through the outlet apertures in supporting members.

4. An apparatus for loading silk or silk-containing textile materials comprising a tank forming a reservoir in the lower portion thereof; a plurality of liquid supply vessels; a plurality of pipes in the tank having fine outlet apertures therein, said pipes acting as supports for the materials to be loaded; means for connecting said members with said vessels to supply liquids to the materials through the apertures; and means for extracting the liquids from the textile materials through the outlet apertures in supporting members.

5. An apparatus for loading silk or silk-containing textile materials comprising a tank forming a reservoir in the lower portion thereof; a plurality of liquid supply vessels; a plurality of pipes in the tank having fine outlet apertures therein, said pipes acting as supports for the materials to be loaded; means for connecting said members with said vessels to supply liquids to the materials through the apertures; means for flushing the materials in the tank; and means connected to the first-named means for extracting the liquids from the textile materials through the outlet apertures in supporting members.

35 In testimony whereof I affix my signature.
RENÉ CLAVEI.
